METER FOR INDICATING VOLTAGE

Leon E. Thomas, Fairfield, Conn., assignor to International Instruments, Incorporated, Orange, Conn., a corporation of Connecticut

Filed Mar. 31, 1966, Ser. No. 1,713

Term of patent 14 years

(Cl. D52—6)

FIG. 1

FIG. 2

FIG. 4

FIG. 3

FIG. 6

FIG. 1 is a view in front elevation of the meter for indicating voltage.

FIG. 2 is a side elevational view thereof.

FIG. 3 is a top plan view thereof.

FIG. 4 is a view in rear elevation thereof.

FIG. 5 is a bottom plan view thereof.

FIG. 6 is a perspective view thereof. The undisclosed side of the control meter is a mirror image of the side shown.

I claim:

The ornamental design for a meter for indicating voltage, as shown and described.
